UNITED STATES PATENT OFFICE.

JOHN J. KENNEY, OF PITTSBURGH, PENNSYLVANIA, ASSIGNOR TO LAWSON MANUFACTURING COMPANY, OF PITTSBURGH, PENNSYLVANIA, A CORPORATION OF PENNSYLVANIA.

DESIGN FOR A GAS HEAT-BURNER.

56,618.

Specification for Design.

Patented Nov. 16, 1920.

Application filed March 8, 1920. Serial No. 364,310. Term of patent 14 years.

To all whom it may concern:

Be it known that I, JOHN J. KENNEY, a citizen of the United States, and a resident of Pittsburgh, in the county of Allegheny and State of Pennsylvania, have invented a new, original, and ornamental Design for Gas Heat-Burners, of which the following is a specification, reference being had to the accompanying drawings, forming a part thereof.

Figure 1 is a plan view of the burner looking toward the fuel orifices; Fig. 2 is a side view of the burner, and Fig. 3 is a bottom view of the burner and is taken from a position opposite that from which Fig. 1 is taken.

My design is characterized by the radially disposed orifice fingers each having a plurality of narrow, transverse orifice slits disposed tangentially of arcs described about the burner center. The horizontally central part of Fig. 2 includes an end view of one of the orifice fingers and discloses the arched top of same which I consider another distinguishing feature of my design.

I claim:

The ornamental design for a gas heat burner, substantially as shown.

JOHN J. KENNEY.
